Patented Nov. 23, 1909.

UNITED STATES PATENT OFFICE.

CHARLES FRANCIS JENKINS, OF WASHINGTON, DISTRICT OF COLUMBIA.

FOLDING BOX.

941,257.

Specification of Letters Patent. Patented Nov. 23, 1909.

Application filed January 26, 1909. Serial No. 474,218.

To all whom it may concern:

Be it known that I, CHARLES FRANCIS JENKINS, a citizen of the United States, residing at Washington, in the District of Columbia, have invented certain new and useful Improvements in Folding Boxes, of which the following is a specification, reference being had therein to the accompanying drawing.

10 The general object of this invention is to produce a box structure having all its parts connected and adapted to lie flat when not desired for use, and to be folded into the form of a closed box, preferably self-sealing, when desired.

15 The invention, although not limited, is more especially intended for producing paper boxes for small articles or merchandise or materials usually delivered in cartons, where hermetic sealing is not essential, and where it is desirable to have somewhat greater strength and durability under rough handling than are found in ordinary cartons, and where at the same time convenience in use and low cost are indispensable.

20 In the accompanying drawings: Figure 1 shows the entire structure in flat form. Fig. 2 is a section on the line 2—2, Fig. 1. Fig. 3 is an end view of the closed box. Fig. 4 is a section on the line 4—4, Fig. 3. Fig. 5 is a front elevation of the closed box. Fig. 6 is a perspective view showing a modification of the flat sheet. Fig. 7 is a section between the ribs of Fig. 6. Fig. 8 is a perspective view of a modification of the corrugated member shown in Fig. 6.

25 In these views, A represents a sheet of heavy paper or paper board after it is formed by creasing it transversely at A', A' to divide it into rectangular sections A² A³ A⁴ A⁵ A⁶, which are to serve as the sealing flap, the top, the side, the bottom, and another side, respectively, of the complete box, and further formed by embossing each section, except the flap, to form parallel, slightly separated ribs, B, B' near and parallel to the parallel free margins of the several sections. The ribs are preferably beveled at each end so that when adjacent sections are 30 so folded as to be perpendicular to each other, the beveled ends of the ribs are pressed together. In order that the ribs may be held against spreading or flattening, and to form strong hinges between the sections, as well as to bind the box at each end and improve its appearance, textile tapes or strips

F of tough paper wide enough to cover the grooves, are cemented to the margins of the sheet A.

35 The ends of the box are plates C, each of which is secured to one of the sections by a hinging strip D in such manner that the end may lie flat upon the section as shown in Fig. 1, or may be swung to perpendicular position and thereby have its hinged edge seated in the space or groove between the adjacent ribs. In this latter position each end lies in the plane of the corresponding grooves in the other sections, and when the latter are properly folded the remaining margins of the end 40 are seated and securely held in the corresponding grooves, the seating being aided by the rounded form of the ribs. The goods to be inclosed may be placed in the box before the cover is folded down, and the cover being 45 closed, the package may be sealed by moistening and pressing down the flap, which is provided with gum at E.

50 In Fig. 6 I have shown the modification of omitting the tapes or strips and the embossing of the sheet A and securing to the face of the sheet strips G of paper or equally rigid material provided with ribs G' analogous to those of the other figures and similarly located with respect to the margins of the 55 sheet, the latter in this case being a plane sheet simply "scored" or grooved along the folding lines. If the strip G be of paper, it is conveniently secured to the sheet by paste, but if it be of metal it may be formed with 60 tongues or spurs H or I, as shown in Figs. 7 and 8.

55 What I claim is:

1. A folding box body consisting of a paper sheet weakened along parallel bending lines and having near each margin transverse to said lines two slightly separated, parallel embossed ribs adapted to receive and hold, between them, box end pieces, when the sheet is folded to box form.

65 2. A folding box having a body sheet weakened along parallel folding lines between the parts destined to form the several sides and a gummed terminal sealing flap, and provided with two sets of pressed-up 70 ribs transverse to said lines and at a short distance from the corresponding margins of the sheet, two box ends each secured to one of said sides alongside one set of said ribs, to lie flat upon the side and to swing into the space 75 between the ribs of that set, and external bands secured to the sheet, extending from

end to end of the same, and spanning, respectively, the space occupied, upon the opposite face of the sheet, by the set of ribs and intervening channel, substantially as set forth.

3. A folding box body consisting of a single paper sheet weakened along parallel bending lines and embossed to form near each margin transverse to said lines two parallel end-retaining ribs each notched at the folding lines, substantially as set forth.
4. A box body sheet having on one face

near each of two opposite margins an end-receiving channel and upon the corresponding parts of its opposite face permanently attached bands transversely bridging the entire channel formation, substantially as set forth.

In testimony whereof I affix my signature in presence of two witnesses.

CHARLES FRANCIS JENKINS.
